UNITED STATES PATENT OFFICE

2,124,311

BUILDING CONSTRUCTION

David V. Nelson, Chicago, Ill.

Application February 18, 1937, Serial No. 126,343

2 Claims. (Cl. 72—118)

My invention relates in general to building construction and has more particular reference to a soundproof suspension means for the support of ceilings and other surfacing elements in a manner suppressing sound transfer through the supported elements. An important object is to provide support means for ceilings and similar surfacing elements in building structures while suppressing or minimizing the transfer of sound through the support.

The utility of sound suppressing support means will be readily perceived when it is understood that ceilings and similar surfacing elements may act as an enlarged sounding board adapted to magnify any vibration transferred thereto from the basic structure on which it is anchored, the provision of means for suppressing sound transfer between the basic structure and the surfacing element being particularly desirable in office buildings and other structures where quiet is especially desired and where the basic structure is subject to vibration initiating from various sources.

Another important object is to provide an improved acoustical structure particularly for use in the suspension of ceilings.

Another important object is to provide an improved acoustical mounting clip for ceilings and the like, the clip being formed to substantially prevent transfer of vibration between a basic structure and a ceiling mounted on the structure by means of the clip.

Another important object is to provide a mounting clip of simplified and inexpensive construction and simplified means for mounting the same in position to support a surfacing element on a basic structure.

Another important object resides in the provision of an improved method for the soundless support of ceiling and similar surfacing elements in a building structure.

These, and numerous other important objects, advantages, and inherent functions of the invention will be more fully understood from the following description which, taken in connection with the accompanying drawing, discloses a preferred embodiment of the invention.

Referring to the drawing:

Figure 1 is a fragmentary perspective view of a ceiling suspension embodying the present invention;

Figure 2 is a perspective view of parts of the structure illustrated in Figure 1;

Figure 3 is a sectional view taken substantially along the line 3—3 in Figure 2; and

Figure 4 is a perspective view of a part of a mounting clip comprising my present invention.

To illustrate the invention, I have shown on the drawing a ceiling structure 11 embodying a soundproof mounting element 13 although it will be apparent that the invention is not necessarily restricted to ceiling structures, but many aspects of the invention may conveniently be employed in soundproof structures generally and particularly in structures requiring soundproof anchorage of surfacing elements.

In the illustrated embodiment, the ceiling structure 11 is mounted or assembled on a basic support structure 15, such as the concrete frame of a building in which the ceiling structure is built. This frame 15 may be formed with wires or cables 17 embedded therein and depending therefrom to form means for suspending the ceiling structure 11 in place. The ceiling structure comprises, in the illustrated embodiment, a plurality of beams 19 extending in preferably and substantially parallel spaced apart relationship and suspended at predetermined spaces with respect to the element 15 of the basic structure by means of the acoustical clips 13 and the cables 17 or other suspension elements for supporting said clips. The clips 13 comprise a channel-shaped element 21 which may be formed of any preferred material although the element 21 may be most conveniently produced as a sheet metal stamping by bending the opposite ends of a rectangular strip of material to form parallel, spaced-apart wall portions 23 interconnected by means of a joining wall 25 clearly shown in Figure 4. Retaining clips or lugs 27 are arranged at the edges of the walls 23 as shown in Figure 4 and these clips may be separate pieces welded or otherwise fastened to the said walls or may be formed integral therewith if desired. Within the channel 21, I arrange a layer 29 of felt or other suitable sound deadening material, said layer preferably comprising a strip of material adapted to fit within and cover the inner walls of the channel. The clips 27 may be folded inwardly as shown in Figure 3 after the acoustical layer 29 is assembled within the channel 21 in order to hold the parts in place, the edges of the clips being adapted to grip the edges of the acoustical layer and to clamp the same against the walls of the channel 21.

It will be noted that the clip 13 is of extremely simple and inexpensive construction, and is adapted to receive the beams 19, which may be steel channels or other preferred forms, within the channel and that when so assembled the

beams will be bedded in the resilient sound deadening acoustical material 29. Of course, any number of mounting clips 13 may be utilized in supporting a beam and the beam may be hung in a desired space merely by wrapping the suspension cables 17 each around a clip 13 in the manner illustrated in Figure 2 of the drawing. Of course, any other kind of suspension element may be used in place of the cables 17, but a cable comprising a flexible wire will not transfer such vibration from the basic structure 15 to the ceiling structure as a more rigid element. Consequently, flexible support elements are preferred. Any vibration which is transferred through the suspension element 17 to the clips 13 will be largely, if not entirely, absorbed in the layer 29 and will not be transferred to the beams 19. The beams 19, therefore, form a substantially soundless support on which the ceiling itself may be erected. The ceiling, of course, may be of any preferred structural form and may comprise a plurality of spaced cross beams 31 anchored in spaced-apart relationship on the beams 19 in any suitable fashion and preferably by means of the tie elements 33 comprising in the illustrated embodiment pieces of wire wrapped around the beams 19 and 31. The spaced beams 31, of course, provide an anchorage for the ceiling 35 which may also be of any preferred material or structural character. In the illustrated embodiment, the ceiling 35 comprises a plaster receiving layer 37, such as expanded metal or other foraminous construction, which is secured on the beams 31 in any convenient or preferred manner, for example, by utilizing the ends of the wires 33 to secure the plaster retaining layer 37 in place. Alternately, if the beams 31 are of wood or other nail receiving material or construction, the layer 37 may be mounted by nail-like fasteners. The layer 37 also may comprise wooden slats nailed in place on the beams 31. The ceiling may be finished by applying a finishing layer 39 on the layer 37 and this finishing layer 39 may be plaster or any other surfacing material depending, of course, upon the nature of the underlying support layer 37 and it is entirely within the conception of my present invention to form a ceiling of boards nailed or otherwise attached directly upon the beams 31. While I have illustrated and described the present invention as applied in ceilings, it is obvious that the sound excluding clip 13 may be utilized to advantage in anchoring other surfacing elements and I, therefore, do not wish, necessarily, to restrict my present invention merely to ceiling structures.

Surfacing elements, such as ceilings, when mounted in the manner heretofore described, are substantially soundproof. That is to say, any vibration originating or initiated in the basic support structure 15 may not reach the surfacing structure 11, all vibration transmitted through the suspension elements 17 being excluded from the surfacing structure by the resilient layer 29. The structure, however, has adequate strength to support the weight of the surfacing structure 11 and if desired, a layer of sand may be spread upon the upper side of the ceiling 35 to increase its sound excluding properties.

It is thought that the invention and its numerous attendant advantages will be understood from the foregoing description, and it is obvious that numerous changes will be made in the form, construction, and arrangement of the several parts without departing from the spirit and scope of the invention or sacrificing its attendant advantages, the form herein described being a preferred embodiment for the purpose of illustrating the invention.

What I claim is new and desire to secure by Letters Patent of the United States is:

1. In a suspended structure comprising a plurality of spaced-apart ceiling bars, the combination of saddles receiving said bars at spaced intervals, said saddles each comprising a plate bent to form a channel having spaced-apart side walls and an integral connecting wall, and a piece of resilient material covering the inwardly facing surfaces of the walls of said channel whereby to resiliently seat a bar in said saddle, and flexible suspension members anchored in and depending from a foundation structure and secured to said saddles to suspend the same and the bars seated therein from said foundation structure.

2. In a suspended structure comprising a plurality of spaced-apart ceiling bars, the combination of saddles receiving said bars at spaced intervals, said saddles each comprising a plate bent to form a channel having spaced-apart side walls and an integral connecting wall, and a piece of resilient material covering the inwardly facing surfaces of the walls of said channel whereby to resiliently seat a bar in said saddle, and flexible suspension members anchored in and depending from a foundation structure, said flexible members comprising wires having dependent portions twisted into loops about said saddles to support the same and the bars seated therein from said foundation structure.

DAVID V. NELSON. 55
